(No Model.)

J. WHEELOCK.

INJECTOR CONDENSER.

No. 257,629.

Patented May 9, 1882.

FIG. 2.

ATTEST:

Philip F. Larmer,
Kawell Larmer.

INVENTOR:

Jerome Wheelock,
By Samuel
Attorney.

UNITED STATES PATENT OFFICE.

JEROME WHEELOCK, OF WORCESTER, MASSACHUSETTS.

INJECTOR-CONDENSER.

SPECIFICATION forming part of Letters Patent No. 257,629, dated May 9, 1882.

Application filed January 23, 1882. (No model.)

To all whom it may concern:

Be it known that I, JEROME WHEELOCK, of the city and county of Worcester, and State of Massachusetts, have invented certain new and useful Improvements in Injector-Condensers for Steam-Engines; and I do hereby declare that the following specification, taken in connection with the drawings furnished and forming a part of the same, is a clear, true, and complete description of the several features of my invention.

In my prior Letters Patent, No. 242,088, dated May 24, 1881, I show a condenser of the class to which my present improvements are applicable, although they may be profitably employed with condensers otherwise constructed. The objects now sought by me are to obtain a uniform discharge of water through or into the condenser-nozzle when a minimum supply of water is employed; also, to provide for the flushing of the water-chamber, so as to remove the accumulated impurities from time to time; and also, to cheaply provide for a properly-shaped and smooth-surfaced nozzle within the usual discharge-pipe.

After a full description of a condenser embodying my several improvements, the features deemed novel will be designated in the several claims hereunto annexed.

Referring to the drawings, Figure 1 is a vertical central section of a condenser containing my improvements. Fig. 2 is a horizontal section of same on line *x*.

The exhaust-pipe *A* communicates with the engine-cylinder in the usual manner. The water-induction aperture *B* communicates with the cold-water source. The annular water-chamber *C* is novel in its character, in that the annular lip *a* is elevated above the bottom of said chamber, thus affording an annular sediment-trap, *b*, within which all earthy matters settle, instead of being directly forced into the annular jet-aperture between said lip *a* and the adjacent outer surface of the tapered annular mouth-piece *c*. The jet-aperture at the lip *a* is, as commonly, of less width than it is below the mouth or entrance, and therefore floating matter in the water is not liable to obstruct any portion of the jet-aperture by entering and becoming wedged therein. For flushing the trap *b*, I have provided a vertical pipe, *d*,

tapped into said trap opposite the entrance to the water-chamber, and by means of a cock, *e*, the contents of the trap may be discharged from time to time through said pipe and cock. 55 As here shown, said pipe at its lower end is provided with an elbow leading into the discharge-pipe *f*, which communicates with the hot-well. The hot-well being usually of sufficient depth to provide for connecting the boiler therewith, at a point midway between the bottom thereof and the water-line therein, permits the heavy matters to settle in said well and the floating matters to remain on top without any of them being liable to be carried 60 to the boilers. 65

It is desirable that the internal conical form of these injector-condensers be of considerable length for obtaining the best results, and this I accomplish economically by locating within 70 the discharge-pipe a conical nozzle, *g*, the upper end of which is coincident with the interior of the cast-iron shell *h*, in which the water chamber and trap *b* is formed, and to which the steam nozzle or mouth-piece *c* is connected, 75 this latter having two annular extensions secured thereto, substantially as in my prior Letters Patent, hereinbefore referred to. The lower end of this nozzle *g* is much smaller than its upper end, and may be slightly submerged by water standing at its level in the hot-well, or slightly above the water-line, as may be preferred. Instead of having an expensive casting to provide for this conical extension, I prefer to construct the nozzle *g* of 80 sheet-iron, and I thereby obtain a smooth and comparatively frictionless interior surface at low cost. This conical extension, separately constructed and located within the discharge-pipe, has value, regardless of whether said 85 nozzle be composed of sheet-iron or cast-iron, because it enables me to make the cast-iron main shell of the condenser, including the clamping-ring *i*, very light and of short length, and it is consequently cheaply molded and 90 cast; and as the nozzle *g* is located within a piece of ordinary straightpipe, *f*, it need not be flanged to afford bolt-sockets, and being externally protected it may be extremely light and inexpensive. 95

It will be seen that in operation the discharge of water over the annular lip *a* into

the jet-aperture will be much more uniform throughout its circumference under a limited supply of water than would be the case if the mouth of the jet-aperture were located below the water-entrance, as heretofore, in which case the portions of the aperture on each side of the water-entrance would be fully supplied, while on the side farthest from said entrance there would be little or no water.

10 I am aware that in pumping-condensers an elevated annular lip within the water-chamber has heretofore been employed; but in such condensers the water is forcibly drawn into the condenser by the forward movement of the 15 pump-piston, which necessitates that the water-chamber and its supply-pipe be always filled with water, for if not thus filled the pump could have no suction control of the water, whereas in an injector-condenser it is frequently desirable, and sometimes necessary, to 20 operate with but little water, and therefore when the water-chamber is supplied with only water enough to barely flow over the top of the lip it will always be distributed with uniformity at all points of the lip and be presented so 25 as to surround the entering column of exhaust-

steam and be enabled to perform condensing duty fully proportionate to its quantity.

Having thus described my invention, I claim as new—

1. In an injector-condenser, the combination, with the water-chamber having an elevated annular lip, a cone projecting downward within said lip, of a conical shell extending below said cone and water-chamber, and a discharge-pipe connected to the lower and small end of said conical shell, substantially as described. 30

2. The combination, with the water-chamber in an injector-condenser, of a sediment-trap and a flush-pipe, substantially as described. 35

3. The combination, with the conical main shell in an injector-condenser and a discharge-pipe connected to the lower end of said shell, of a tapered nozzle extending downwardly within said discharge-pipe, and in communication at its upper end with the interior of the conical shell, substantially as described. 40 45

JEROME WHEELOCK.
